FIG. 1

FIG. 2

FIG. 3

INVENTOR
Catherine V. Wilson,
By Owen, Owen & Crampton,
Her atty.

UNITED STATES PATENT OFFICE.

CATHERINE V. WILSON, OF TOLEDO, OHIO.

FLAT-IRON HOLDER.

1,292,977.

Specification of Letters Patent. Patented Jan. 28, 1919.

Application filed January 8, 1918. Serial No. 210,839.

To all whom it may concern:

Be it known that I, CATHERINE V. WILSON, a citizen of the United States, and resident of Toledo, in the county of Lucas and State of Ohio, have invented a certain new and useful Flat-Iron Holder; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to holders or supports for flat-irons, and particularly to those of the type adapted to be permanently secured to ironing-boards.

The object of my invention is the provision of an improved device of the class described, which is simple and efficient in its construction and on which an electric iron may be left standing for any length of time with the current on without liability of burning the board or member on which the support is mounted. Other objects and advantages of the invention will be apparent from the following detailed description.

While the invention, in its broader aspect, is capable of embodiment in numerous forms, a preferred embodiment thereof is illustrated in the accompanying drawings, in which—

Figure 1 is an inner end elevation of a holder embodying my invention, with a part broken away and with the board on which mounted in transverse section. Fig. 2 is a side elevation thereof, with a part broken away, and Fig. 3 is a top perspective view 40 of an end portion of a board with the holder mounted thereon.

The flat-iron holder or support embodying my invention comprises the bottom 1, preferably formed of sheet metal and provided with longitudinally extending flutes or corrugations and having the opposite side and rear end edges thereof turned up to provide a confining wall or flange 2. The metal or material forming the wall 2, after 50 extending upward a short distance, is turned outward and downward to form a leg or supporting flange 3, which extends downward below the plane of the bottom 1 and has its lower edge turned outward to form 55 a foot-flange 4. The bottom 1 of the holder, at the front end or open side thereof, is pro-

vided with an extension 5, which declines gradually outward from the plane of said bottom to the plane of the foot-flange 4, said extension being preferably free from corrugations, as shown.

The holder is intended to be permanently mounted on an ironing-board 6, or other suitable support, by securing the foot-flange 4 and the outer end of the extension 5 thereto by screws 7, or in any other suitable manner, and it is preferable in practice, but not necessary, to space the holder from the board 6 by a sheet 8 of asbestos or other suitable heat insulating material. It is preferable to 70 provide the leg-flange 3 at intervals with openings 9 to permit a free circulation of air under the bottom 1, and also to provide air circulating openings 10 in the channels of the bottom.

In applying the holder to an ironing-board it is preferable to place it at one end of the board beyond the customary cloth covering or pad 11, with the extension 5 projecting lengthwise of the board toward 80 the covering or padding and terminating substantially in end abutment with the adjacent end edge thereof, as shown, with the top surface of the end edge of the tongue substantially flush with the top surface of 85 the covering, so that an iron can be freely slid from the covering onto and up the extension 5 to the bottom 1 without raising the iron from the board.

It is evident that I have provided a simple and efficient flat-iron support, which will prevent the liability of fire by reason of a heated iron being left standing for any considerable time on the support, and that it also saves considerable energy on the part of 95 the person ironing by reason of the holder extension 5 terminating at its outer end substantially flush with the surface of the board covering.

I wish it understood that my invention is 100 not limited to any specific construction, arrangement or form of the parts, except in so far as such limitations are specified in the claims.

Having thus described my invention, what 105 I claim as new, and desire to secure by Letters Patent, is—

1. A flat-iron holder comprising a bottom portion, with its side and outer end edges extending upward a short distance to 110 form retaining walls and then outward and downward to form a leg-flange which ex-

- tends below the plane of the bottom, and the front end edge of the bottom having an outward extension which declines therefrom and terminates substantially in the plane of the lower edge of the leg-flange.
2. A flat-iron holder comprising a bottom, the side and rear end edges of which extend upward a short distance to form a retaining wall and then outward and downward to form a leg-flange, with its lower end extending outward to form a foot-flange which is disposed below the plane of the bottom, said bottom and leg-flange having air circulating openings therein, and the forward end of the bottom having an outward extension which declines therefrom and terminates substantially in the plane of the lower edge of said foot-flange.
3. A flat-iron holder formed of sheet metal and comprising a corrugated bottom having the side and rear end edge thereof extending upward a short distance to form a retaining wall and then extending outward and downward to form a leg-flange, said bottom and leg-flange having air circulating openings therein, and the forward edge of the bottom being extended outward and

downward on a gradual decline to the plane of the lower end of the leg-flange and having its outer end portion plain.

4. The combination with an ironing-board having a padded covering on a portion thereof, of a flat-iron holder mounted on said board at one end of said covering, said holder comprising a bottom portion which is corrugated lengthwise thereof and spaced from the board and having its side and rear end edges extending upward a short distance to form a retaining wall and then extending outward and downward to form a leg-flange, with the lower end thereof extending outward to form a foot-flange for resting on the board, said bottom and leg-flange having air circulating openings, and the bottom having a plain outward extension at its forward end which declines therefrom and terminates at its outer end in substantial abutment with the adjacent end edge of said covering flush therewith, and means securing the holder to the board.

In testimony whereof, I have hereunto signed my name to this application.

CATHERINE V. WILSON.
